UNITED STATES PATENT OFFICE.

OTTO WUNDRACK, OF CHICAGO, ILLINOIS.

FURNACE.

SPECIFICATION forming part of Letters Patent No. 757,536, dated April 19, 1904.

Application filed May 31, 1902. Serial No. 109,626. (No model.)

To all whom it may concern:

Be it known that I, OTTO WUNDRACK, a subject of the Emperor of Germany, residing at Chicago, in the county of Cook and State of Illinois, have invented a certain new and useful Improvement in Furnaces, of which the following is a specification.

My invention relates to furnaces for boilers or other purposes, and has for its object a new and improved construction of which the following is a description, reference being had to the accompanying drawings, wherein—

Figure 1 is a vertical section through a furnace embodying my invention. Fig. 2 is a section on line 2 2, Fig. 1, with parts omitted. Fig. 3 is a section on line 3 3, Fig. 1, with parts omitted. Fig. 4 is a view of one of the grate-bars. Fig. 5 is a section on line 5 5, Fig. 4. Fig. 6 is a section through the controlling device for admitting the air. Fig. 7 is a front view of the same with parts omitted. Fig. 8 is a front view of the furnace. Fig. 9 is a section on line 9 9, Fig. 1.

Like letters refer to like parts throughout the several figures.

My present invention relates to the construction of the grate of the furnace and also to a construction and arrangement for consuming the smoke produced by the fire. In the construction illustrated in the drawings I have provided on each side of the grate a series of openings or passage-ways A, B, and C, through which air passes. The front doors of the grate are preferably kept closed, so that no air is admitted except through these passage-ways A, B, and C. The passage-ways C, of which there is one on each side of the grate, pass from the front to the back of the furnace along the side, so that the air passing therethrough becomes heated. This air then enters the chamber C' at the back of the furnace and passes through the opening C² below the grate, so as to supply the fire with oxygen. In this instance it will be seen that the fire is supplied with heated air instead of cold air.

The passage-ways A, one on each side of the grate, pass along the sides of the furnace and then pass upwardly and connect with the chamber A' back of the grate.

The grate is made up of a series of hollow grate-bars D, connected at one end to the chamber A' and at the other end to the chamber A², so that the air from the passage-ways A enters the chamber A' and passes through the grate-bars into the chamber A². These grate-bars are preferably bent or formed with obstructing-surfaces against which the air strikes in its passage through them. This result may be produced in various ways, and, as herein shown, the grates are made with waves or wave-shaped, the several parts being bent out of alinement, as it were, so as to form the obstructing or deflecting surfaces D', against which the air strikes. The air in passing through these grate-bars cools them and prevents them from being burned, and at the same time the air is heated to a comparatively high temperature. This air after passing through the grate-bars enters the chamber A² and then passes along on each side of the grate to the rear thereof and then upwardly into the chamber A³. This chamber A³ runs along the back of the grate and is provided with a series of openings A⁴, through which this heated air passes, said heated air striking the smoke as it is passing from the grate. Since this air is at a high temperature, it will consume the smoke, causing the carbon to be burned. The air entering the passage-ways B passes back and forth along the hot sides of the grate and then enters the passage-way B', extending across the top of the grate, and then communicates with the chamber B², which extends along the full length of the grate. This chamber is provided with a series of openings B³, which correspond to the opposite openings A⁴. The air in its passage through the various passage-ways in proximity to the fire becomes heated to a comparatively high temperature and then passes out through these openings B³ and strikes the smoke as it comes from the grate, the hot air consuming the carbon, and thus preventing smoke. The two blasts of hot air from the several opposed openings A⁴ and B³ thus commingle, as it were, and the entire area through which the smoke passes is thus covered and all of the smoke consumed.

The opposed openings B³ and A⁴ are located, as will be seen, above the fire and at a narrow

contracted part of the passage-way through which the products of combustion pass and are opposed to each other, so that the currents of heated air are forced toward each other.

5 These currents of air meeting at this point hold the soot momentarily until it is burned by the fire, the heated air aiding in this process. The arch or projecting part provided with the openings A³ is also an important feature in the practical working of my invention.

10 As shown in the drawings, I have illustrated the air passing through the hollow grate-bars as being used when heated to aid in consuming the smoke; but it is of course evident that this air might be disposed of in other ways. It is further evident that the several passage-ways may be varied in construction, arrangement, and number and that the other parts may also be varied without departing 15 from the spirit of my invention. I therefore do not limit myself to the construction shown. The passage-ways A, B, and C are provided with means for controlling the amount of air admitted thereto. As herein 20 shown, this means consists of a rotatable controlling device E at the end of the passage-way, which may be moved so as to vary the opening through which the air is admitted or to entirely close said opening, said controlling device preferably provided with a suitable handle or the like E', by which it may be 25 easily manipulated.

It will be noted that since the discharges or openings B³ and B⁴ communicate with the flue 30 or discharge for the furnace the draft produced by the fire will also produce a draft in these several passage-ways, so as to draw the air through them while the fire is burning.

As herein illustrated, the air passes to the 35 back of the grate through the passage-ways A at the sides and then passes in a forward direction through the grate-bars and then passes back along the sides of the grate through the passage-way A² into the chamber A³. This 40 chamber A³ extends along the wall in proximity to the face of the contracted opening through which the gases pass, and there are provided a series of separated openings connecting this chamber with the said contracted 45 opening, so that the air is divided into a series of separated streams. The chamber B² extends along the wall near the passage-face of the contracted opening and is provided with a series of similar separated openings. It will 50 also be noted that the currents of air forced toward each other on the opposite sides of this contracted opening are independently regulated, so that the amount of air and the force with which it is projected may be properly 55 regulated and the best results secured. The desirability of this feature will be readily seen 60 when it is remembered that the upward current through the contracted opening is not uniform across the entire area of this space.

I claim—

- 65 1. A furnace comprising a series of hollow grate-bars provided with connections which lead to the external atmosphere by means of which air may be drawn therethrough, a contracted opening above said grate-bars through 70 which the products of combustion pass, a chamber in the wall opposite one face of said contracted opening and extending therealong, a connection leading from said hollow grate-bars to said chamber, a forwardly-projecting 75 part in front of said chamber provided with a substantially vertical face and a series of separated openings in said face and connecting said chamber with said contracted opening.
2. A furnace provided with a series of passage-ways associated therewith through which air is passed so as to become highly heated, and which passage-ways discharge substantially horizontally on opposite sides of the furnace above the fire, so that this heated air is 80 brought into contact with the smoke from the fire so as to consume it, the discharge-openings on the opposite sides of the furnace opposed so that the currents of air are forced 85 toward each other and a series of hollow grate-bars connected therewith so as to form parts 90 of some of said passage-ways and through which a portion of the air passes so as to cool the grate-bars.
3. The combination with a furnace of a series of hollow grate-bars, a passage-way at the side of the furnace leading to the rear thereof, a connection between said passage-way and the rear end of said hollow grate-bars, a second passage-way in the wall of said furnace 100 and a connection between the front of said bars and said passage-way, a contracted opening above the grate, one or more discharge-openings in the wall thereof, said discharge-opening connected with said passage-way. 105
4. The combination with a furnace of a series of hollow grate-bars, a connecting-chamber at each end thereof, two passage-ways in the wall of the furnace, one leading to the external atmosphere and to the connecting-chamber at one end of the grate, the other leading from the connecting-chamber at the other end of the grate to a point above the 110 grate-bars.
5. A furnace comprising a series of hollow 115 grate-bars provided with connections which lead to the external atmosphere, by means of which air may be drawn therethrough, said grate-bars also provided with a connection leading to the furnace-chamber above the 120 grate, a passage-way leading along the side of the furnace so that the air therethrough will be heated, and provided with a connection leading to the furnace-chamber above the 125 grate said connections provided with opposed discharge-openings so that the currents of air are forced toward each other above the fire, thus coming into contact with the smoke, and

means for independently regulating the currents of air supplied to the opposed discharge-openings.

6. A furnace comprising a series of hollow grate-bars provided with connections which lead to the external atmosphere by means of which air may be drawn therethrough, a contracted opening above said grate-bars through which the products of combustion pass, a chamber in the wall opposite one face of said contracted opening and extending therealong, a connection leading from said hollow grate-bars to said chamber and a series of separated openings connecting said chamber with said contracted opening, a second chamber in the

wall opposite the other face of said contracted opening and extending therealong, a series of independent openings connecting said chamber with the contracted opening and a passage-way connected with said chamber and extending along the side of said furnace, said passage-way communicating with the external air and means for separately and independently regulating the current of air passing through the openings on the opposite sides of said contracted opening. 25
